UNITED STATES PATENT OFFICE.

SEYMOUR A. ROUSE, OF CHICAGO, ILLINOIS.

ARMORED LINER FOR PNEUMATIC TIRES.

1,227,673.

Specification of Letters Patent. Patented May 29, 1917.

Application filed June 1, 1915. Serial No. 31,562.

To all whom it may concern:

Be it known that I, SEYMOUR A. Rouse, a citizen of the United States, residing at Chicago, in the county of Cook and State of Illinois, have invented certain new and useful Improvements in Armored Liners for Pneumatic Tires; and I do hereby declare the following to be a full, clear, and exact description of the invention, such as will enable others skilled in the art to which it appertains to make and use the same.

This invention relates to armored reliners for insertion into pneumatic tires, and the primary object of the invention is to provide an armored liner, which is practically puncture-proof, and one which is rendered practically puncture-proof by insertion of a plurality of connected metallic disks within the tread section thereof, for preventing nails, or other foreign articles from penetrating through the inflatable inner tube of the tire, and also for eliminating the liability of blow-outs.

Another object of this invention is to connect the disks which are inserted or embedded in the liner, in relatively spaced relation to each other for facilitating the forming or building up of the liner, and further to copperize the disks so that they may be securely attached to the rubber and fabric portions of the liner by vulcanizing.

Another object of this invention is to emboss the disks so as to prevent them from slipping or shifting out of their proper positions should the vulcanizing be imperfect.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:—

Figure 1 is a cross sectional view through a tire shoe, showing the liner inserted therein,

Fig. 2 is a plan view, showing parts of the liner broken away,

Fig. 3 is a view illustrating the process of forming the liner, and showing the various parts prior to the vulcanizing thereof,

Fig. 4 is a sectional view through the

liner, showing the parts compressed and vulcanized,

Fig. 5 is a plan view of a section of a sheet of disk used in the construction of the tire shoe,

Fig. 6 is a fragmentary view of a modified form of a sheet of disk.

Fig. 7 is a fragmentary view of still another modified form of the sheet of disk, and

Fig. 8 is a cross sectional view through a pneumatic tire shoe, showing a modified use of the liner.

Fig. 9 is a view of a modified form of the embossed disks.

Fig. 10 is a cross sectional view of the disks shown in Fig. 9.

Referring more particularly to the drawings, 1 designates the completed liner, as an entirety, which is shaped to fit the interior of a tire shoe of ordinary construction. The liner is adapted for being cemented within the shoe, as indicated at 2 in Fig. 1 of the drawings, for protecting the inner inflatable tube 3. The liner 1 is armored for preventing the puncturing of the inner inflatable tube 3, by means of a plurality of disks 5. The disks 5 are formed in sheets and extend about the entire circumference of the liner, being held in relatively spaced relation to each other by means of tongues 6. The liner 1 has two sheets of disks embedded therein, which are spaced from each other, and the disks are positioned for overlapping each other, for forming substantially a solid metallic casing within the liner, thereby reinforcing the tire and protecting the tube 3 against puncture, blow-outs or the like.

In Fig. 6 of the drawings, a sheet of disks is shown, wherein the central row 8 of the disks are tied or connected longitudinally of the sheets, by tongues 9. The side rows 10, 11, 12 and 13 of the disks are connected to the central row 8, by laterally extending tongues 14 and 15. The disks in the side rows 10, 11, 12 and 13, are connected for forming laterally extending connected rows of disks, which facilitate the bending of the sheet of disks for conforming to the configuration of the tire, and also add to the resiliency of the sheet of disks during the operation of the tire.

The disks in the outermost side rows 12 and 13 are narrower than the disks in the side rows 10 and 11, and the latter disks are

narrower than the disks in the central row 8, the disks gradually decreasing in width as they extend outwardly from the central row of disks.

- 5 In Fig. 5 of the drawings, a slightly modified form of the sheet of disks is shown, wherein the two central rows 16 and 17 are tied or connected longitudinally of the sheet by tongues 18 and 19. The side rows of 10 the sheet illustrated in Fig. 5, are tied or connected to the two central rows 16 and 17 by laterally extending tongues 20, and the outermost side rows are connected to the side rows 21 and 22, which are connected 15 to the central rows 16 and 17, by tongues 23. The disks in the outermost row are narrower than the disks in the rows 21 and 22, which latter disks are also narrower than the disks in the central rows 16 and 17, as shown in 20 Fig. 6.

In Figs. 9 and 10 a modified form of the embossed disks is shown, which illustrates the disks having an emboss formed thereon in circular formation.

- 25 In Fig. 7 of the drawings, still another modified form of the disk sheet is shown, wherein all of the disks are tied or connected both longitudinally and laterally of the sheet, by tongues 30, and in which all of the 30 disks are of a uniform width.

In all of the modified forms, the disks are embossed in any suitable manner, as is shown at 25, so as to prevent the slipping about or shifting of the disks, should the 35 vulcanizing of the tire be imperfect.

The disks are also copperized, for rendering them susceptible to the vulcanizing action of the rubber and impregnated fabric used in the construction of the tire shoe.

- 40 In forming the armored liner, for a pneumatic tire, a sheet of impregnated fabric, indicated at 35^a, in Fig. 3 of the drawings, is placed upon a table or other support, and a sheet of rubber 35 is placed upon the upper 45 surface of the impregnated fabric 35^a, after which a sheet 33 of connected embossed copperized disks is placed upon the upper surface of the sheet 35. A sheet of rubber 31 is then placed upon the sheet of disks 33, 50 and a sheet of rubber 34 is placed upon the upper surface of the disks, after which a second sheet of impregnated fabric, indicated at 34^a is placed upon the upper surface of the sheet 34 of rubber. After the 55 sheets have been assembled, they are subjected to pressure or rolled to allow any pockets of air to escape, after which they are again rolled or subjected to pressure for forcing the air out of the indentations formed in the disks, by embossing them, and also for properly positioning the various sheets in engagement with each other. After the various sheets have been rolled or 60 pressed together, they are vulcanized, which causes all of the sheets to adhere one to the

other, and form the complete liner 1. The liner is inserted in the interior of the tire 2, and cemented to the inner wall of the shoe, as is clearly shown in Fig. 1 of the drawings.

By connecting the disks, the handling thereof, for embossing, copperizing and for properly placing them upon the opposite sides of the sheet 31 of rubber, is greatly facilitated, and the bosses on the disks prevent their shifting or slipping, in case the vulcanizing is imperfect, as has been previously stated.

While in the foregoing, and in the drawings, only two sheets of disks have been 80 shown, it is to be understood that any number of sheets of disks desired may be employed, and a corresponding number of sheets of rubber for forming the tire.

In placing the sheets 32 and 33 upon the 85 rubber sheets, the disks are disposed in overlapping positions with respect to each other, so as to form substantially a solid sheet of metal within the tire shoe.

In Fig. 8 of the drawings, a modified use 90 of the liner is shown. In this view, an ordinary shoe for a pneumatic tire is employed, which includes a tread section 40, and a protector 41, which is placed between the outer surface of the inner casing 42 and 95 the inner surface of the tread section 40.

The protector 41 is armored for preventing the puncturing of the inner inflatable tube, and is constructed in accordance with the manner set forth for constructing the re- 100 liner 1.

From the foregoing description taken in connection with the accompanying drawings, the advantages of the construction of the improved armor tire, and the method of 105 assembling or constructing the armor tire will be readily apparent to those skilled in the art to which this invention appertains and, while in the foregoing description, the principle of the operation of this invention 110 has been described, together with various features of construction, it is to be understood that certain minor features of construction, or the method of operation, may be altered to suit practical conditions, provided such alterations are comprehended within the scope of what is claimed.

What is claimed is:—

1. As a new article of manufacture, an armor for pneumatic tires comprising a plurality of metal disks, and integral connections securing the disks together in strip formation, the outermost disks in said strip being free from connection longitudinally of the strip, said connections being pliable 125 to permit the strip to be bent to conform to the configuration of a tire so it may be embedded therein.

2. As a new article of manufacture, an armor for pneumatic tires comprising a plu- 130

rality of metal disks arranged in a strip, connections formed integrally with the inner disks and connecting them longitudinally of the strip, and connections formed integrally 5 with the outer disks and connecting them laterally of the strip and to said longitudinally connected disks, said outer disks being free from connection longitudinally of the strip.

10 3. As a new article of manufacture, a puncture preventing strip for pneumatic tires comprising a plurality of disks arranged in rows longitudinally with and laterally of the strip, means connecting the 15 central row of disks longitudinally of the strip, means connecting the lateral rows of disks laterally of the strip and to the central row, the outermost disks in said lateral rows being free from connection longitudinally 20 of the strip.

4. As a new article of manufacture, a puncture preventing strip for pneumatic tires comprising a plurality of pliable metal disks, pliable tongues formed integral with 25 the longitudinal central disks of said strip and uniting them in a row longitudinally of the strip and laterally extending pliable tongues connecting the side disks of said strip in rows laterally of the strip and to 30 said central disks.

5. As a new article of manufacture, a puncture preventing strip for pneumatic tires comprising a plurality of pliable metal disks, pliable tongues formed integral with 35 the longitudinal central disks of said strip and uniting them in a row longitudinally of the strip, laterally extending pliable tongues formed integral with and uniting the side disks of said strip in rows laterally 40 of the strip and to said central disks, the disks in the edge rows being narrower than the disks in the central and intermediate rows.

6. As a new article of manufacture, a puncture preventing strip for pneumatic 45 tires comprising a plurality of metal disks arranged in rows, tongues uniting the central longitudinal row of disks, laterally extending tongues uniting the side rows of 50 disks in rows laterally of the strip, said disks being embossed.

7. As a new article of manufacture, a

puncture preventing strip for pneumatic tires comprising a plurality of pliable metal disks, pliable tongues formed integral with 55 the longitudinal central disks of said strip and connecting them in a row longitudinally of the strip, laterally extending pliable tongues connecting the side disks of said strip in rows laterally of the strip and to 60 said central disks, the disks in the edge rows being narrower than the disks in the central and intermediate rows, said disks being embossed.

8. As a new article of manufacture, a puncture preventing strip for pneumatic tires comprising a plurality of metal disks arranged in rows, tongues uniting the central longitudinal row of disks, laterally extending tongues uniting the side rows of 70 disks in rows laterally of the strip, said tongues being formed integrally with said disks and lying in the same horizontal plane with the disks.

9. As a new article of manufacture, a puncture preventing strip for pneumatic tires comprising a plurality of pliable metal disks, pliable tongues formed integral with 75 the longitudinal central disks of said strip and connecting them in a row longitudinally 80 of the strip, and laterally extending pliable tongues connecting the side disks of said strip in rows laterally of the strip and to said central disks, said tongues lying in the same horizontal plane with said disks. 85

10. As a new article of manufacture, an armor for pneumatic tires comprising a plurality of metal disks, integral connections securing the disks together in strip formation, the disks along the edges of said strip being free from connection longitudinally of the strip, said connections being pliable to permit the strip to be bent to conform to the configuration of the tire, so it may be embedded therein, said edge disks being narrower than the intermediate disks, said disks being embossed. 90

In testimony whereof I affix my signature in presence of two witnesses.
